UNITED STATES PATENT OFFICE

2,655,120

DEVICE FOR RECRIMPING THE HEAD
SEAMS OF DRUMSHenry F. Niemann, Sedalia, Mo., assignor of
fifty per cent to Sherman D. Beckley, Sedalia,
Mo.

Application November 1, 1951, Serial No. 254,352

3 Claims. (Cl. 113—7)

1

This invention relates to a drum sealer and particularly for a manually operated device to be put on a drum to seal a leak therein.

Metal drums for containing liquid material are constructed as substantially cylindrical bodies with a bottom and a head rigidly secured therein by means of a double reverse crimp seal. These seals are made either by inserting a sealing gasket between the material before it is crimped or by crimping it down and preferably welding or otherwise uniting the crimped edges. Because of the rough handling that these drums receive they frequently spring leaks through these crimped edges. It has heretofore been found necessary to weld or reweld the crimped edges to stop the leak. Since the welding expands the metal adjacent to the weld it has been found necessary to run the weld completely around the seam in order to provide a leak proof joint. Also if the leak is found after the drum is filled it is usually necessary to completely empty and clear the drum to prevent explosion during the sealing operation.

The present invention provides a means for recrimping the rims of steel drums in order to seal the leak without removing the contents of the drum. Since the present sealing method crimps only the leaky portion of the seam it is only necessary to extend the crimping action over the leaking part of the joint.

Therefore, in accordance with the present invention there is provided a base on which is mounted a beaded roller and a pressure block pivotally mounted on the base and pressed toward the base. A crimping roll is mounted in the pressure block and the crimping roll and beaded roll is seated on the crimped edge of the drum and pressure is applied while the crimping roll is turned to crimp and press the sealed edges into leak-proof engagement.

It is accordingly an object of this invention to provide an improved crimping roller.

It is a further object of this invention to provide an improved drum sealer.

It is a further object of this invention to provide a drum sealer that may be utilized to seal a drum while it is full of liquid.

It is a further object of this invention to provide a drum sealer that only need be applied to the leaking portion of the barrel.

It is a further object of this invention to provide a drum sealer which is readily portable from drum to drum.

It is a further object of this invention to provide a drum sealer that can be manually operated by one man.

Other objects and many of the attendant advantages of this invention will be apparent from the following detailed description taken in conjunction with the accompanying drawings in which:

2

Figure 1 is a top plan view of a drum sealer in place on a drum;

Figure 2 is a bottom plan view of a sealer;

Figure 3 is a cross section through the drum sealer taken substantially on the plane indicated in the line 3—3 of Figure 1 and showing the pressure block applied between the crimping roller and the beaded roller;

Figure 4 is an enlarged perspective view of the yoke; and

Figure 5 is an enlarged perspective view of the pressure block.

In the exemplary embodiment of the invention, the drum 10 is provided with a bottom 12, the drum 10 and the bottom 12 being rigidly and permanently connected to each other by means of a double inverse bend or crimp 14. The crimp 14 may be welded or may have material of various kinds between the bends to produce a leak-tight joint. Also the materials may be welded to each other braised, soldered or otherwise integrally united.

If rough handling or other accident should produce a leak to the seal 14 it can be recrimped by means of a sealer presently to be described.

The sealer itself comprises a base 16 preferably of cast iron having an upstanding bracket 18 at one edge thereof. The bracket 18 is preferably provided with a central passage so the bracket is substantially channel shape having two extending flanges 20 and 22, defining a channel 24 therebetween. A pressure block 26 has an extending rib 28 which substantially fits in the channel 24. Transverse passage 30 provided adjacent the top end of the rib 28 cooperates with passages 32 and 34 in the flanges 20 and 22. A rod 36 extends through the flanges 20 and 22 and the rib 28 so that the block is pivotally mounted in the bracket 18. The rib 28 is rounded off at the upper corner 38 so that the block 26 may freely swing outwardly from the bracket 18.

The pressure block 26 is provided with a longitudinal passage 40 for receiving the shaft 42 of a crimping roller 44 which is mounted on the lower end of the block 26 and journaled therein by means of a shaft 42. The shaft 42 extends upwardly out of the block 26 and is provided with recesses 46 adjacent the top thereof and a collar 48 is mounted on the shaft 42 and secured thereto by means of set screws 50 so that the shaft 42 is retained in the bore 40 to properly mount the crimping roll 44 at the lower end of the block 26. Bearing washer 52 is preferably inserted between the top of the roller 44 and the bottom of the block 26. The upper end of the shaft 42 extending beyond the collar 48 is provided with a non-round section, such as a square section 54 for receiving any suitable handle for applying the necessary pressure by turning the roll 44. In the present example, a double handled wrench-like extension is provided with an opening 58

snugly engaging the square portion 54 of the shaft 42 so that the roller 44 may be conveniently turned by a manual operation.

The base 16 is provided with a vertically extending passage 60 substantially parallel to the upstanding bracket 18. A beading roller 62 is provided with a shaft 64 which extends through the passage 32 to journally mount the shaft 52 in the base 20 so that the beading roller 62 is journally mounted with respect to the base 16. A bearing washer 66 is usually installed between the top of the roller 62 and the bottom of the base 16. The top of the shaft 64 is provided with an undercut section 68 and a collar 70 to be mounted on the top of the shaft 64 and secured thereto by means of a set screw 72 engaging the undercut portion 68 of the shaft 64 to retain the shaft 64 in mounted relation in the base 16.

A pair of ears 76 and 78 mounted on the base in spaced relation to the upstanding flange members 20 and 22 are provided with transverse openings 80 and 82 for receiving pins 84 and 86. A yoke 90 is pivotally mounted on the pins 84 and 96 by means of transverse passages 92 and 94. The yoke 90 is substantially a bifurcated member having a web 96 and a pair of arms 98, 100. The top corners of the arms 98 and 100 are rounded off as at 102 so that the yoke 90 may be raised upward but when it drops down it will be stopped by the square corner 103 and will not pass below center.

The block 26 is provided with an outwardly extending ledge 104 having a depression 106 therein. The web 96 of the yoke 90 is provided with a bore 108 in which is threadedly engaged a set screw 110 having a knurl head 112. The end 114 and the screw 110 is engaged in the recess 106 and by tightening the screw 110 the block 26 is pressed toward the base 16 so that the crimping roll 44 is pressed toward the beading roller 62. The pressure between the two being determined by the set screw 110. Preferably a lubricant passage 116 is provided in the block 26 so that the journal bearing of the shaft 42 may be constantly lubricated.

In order to maintain the pressure normal between the beading roll 62 and the crimping roll 42 a plurality herein shown as a pair of guide rolls 120 and 122 are journaled in the base 16 and retained therein by collars in substantially the same manner as indicated with the roller 62. Size of these rollers 120 and 122 will depend on the size of the drum being operated on for the larger size, 55 gallon drum, large size rollers 120 and 122 will be used but for a 30 gallon drum a slightly smaller size of guide rollers 120 and 122 will be utilized.

In order to prevent injury to the device and excessive accumulation of dirt on the fastening collars, a cover 125 is constructed of suitable material such as sheet metal and provided with ears 126 and 128 which receive suitable fasteners such as screws 130.

In the operation of the device screw 110 is opened and the bracket or yoke 90 is raised up so that the pressure block may swing out and allow the crimping roller 44 to be adjusted onto the rim of a drum 10. The yoke 90 is then put in place and the screw end 114 inserted in the recess 106 and the screw tightened by means of the head 112 to supply the necessary pressure between the rollers 44 and 62 after which the handle bar 56 is adjusted on the squared portion 54 and the shaft 42 rotated in any direction to advance the crimping roller around the leaking portion of the seam 14.

While for purpose of illustration a particular embodiment of the invention has been shown and described according to the best present understanding thereof, it will be apparent that many changes and modifications, may be made therein, without departing from the true spirit of the invention.

Having described the invention, what is claimed as new is:

1. A drum sealer comprising a base, an upstanding bracket on said base, a pressure block pivotally attached to said bracket adjacent the top thereof, a pair of ears on said base adjacent the bottom of said bracket, a yoke pivotally mounted on said ears, a screw in said yoke for pressing said pressure block toward said base, a longitudinal bore in said pressure block, a crimping roll including a shaft, said shaft journaled in said bore, means for rotating said shaft in said bore, a plurality of bores arranged in arcuate formation in said base, a beaded roller, a shaft on said roller, said shaft journaled in the central bore of said bores, a plurality of guide rollers mounted in said arcuately arranged bores adjacent the beaded roller, said guide rollers maintaining a pressure point normal to said crimping and beaded roller.
2. A drum sealer comprising a base, an upstanding bracket on said base, a pressure block pivotally attached to said bracket adjacent the top thereof, a pair of ears on said base adjacent the bottom of said bracket, a yoke pivotally mounted on said ears, a screw in said yoke for pressing said pressure block toward said base, a longitudinal bore in said pressure block, a crimping roll including a shaft, said shaft journaled in said bore, a plurality of bores arranged in arcuate formation in said base, a beaded roller, a shaft on said roller, said shaft journaled in the central bore of a plurality of said bores, a guide roller mounted in a bore adjacent each side of said beaded roller for centering the pressure between said crimping roller and said beaded roller, a cover mounted on said base.
3. A drum sealer comprising a base, an upstanding bracket adjacent one edge of said base, a pressure block, said pressure block being pivotally attached to said bracket adjacent the end remote from said base, said pressure block having a longitudinal bore therethrough, a shaft journaled in said bore, a crimping roller rigidly mounted on the lower end of said shaft, a beading roller journaled on said base in opposed relation to said crimping roller, a yoke including a pair of arms, said arms being pivotally mounted on said base, a set screw threadedly mounted in said yoke and engaging said pressure block for pressing said crimping roller toward said beading roller, and means for rotating the shaft carrying the crimping roller.

HENRY F. NIEMANN.
